FROSTED FOOD DIVIDER DISPLAY RACK

Lowell J. Schettler, Tomah, Wis., assignor to Reddi-Wip,
Inc., St. Louis, Mo., a corporation of Missouri

Application July 3, 1953, Serial No. 25,792

Term of patent 14 years

(Cl. D80—10)

The figure is a perspective view of a frosted food divider display rack showing my new design.

I claim:

The ornamental design for a frosted food divider display rack, substantially as shown.
